M. F. ROSEN

ARCH SUPPORT

Filed April 15, 1925

Patented Oct. 2, 1928.

1,686,034

UNITED STATES PATENT OFFICE.

MATHIAS F. ROSEN, OF DETROIT, MICHIGAN.

ARCH SUPPORT.

Application filed April 15, 1925. Serial No. 23,230.

My invention relates to a new and useful improvement in an arch support, which is adjustable for effecting varying degrees of elevation, so as to permit the wearer of the arch support to gradually raise the arch of his support to engage the foot at different elevations, the raising of the arch to the different elevations being accomplished by manual operation of the wearer, so that the wearer 5 may gradually accustom his foot to the elevated position to which the arch support will raise the arch of the foot.

Another object of the invention, is the provision of an arch support having an adjustable member, operated by a chain, and adapted for being mounted on a main supporting plate, and for, in its adjusting movements, drawing the one end of said mounting plate and pushing on the other end.

20 Another object of the present invention, is the provision of an arch support having an adjusting member, adapted for determining the amount of flexing of the arch support upon a longitudinal and lateral shifting.

25 Other objects will appear hereinafter.

The invention consists in the combinations and arrangements of parts hereinafter described and claimed.

The invention will be best understood from 30 a reference to the accompanying drawings which form a part of this specification and in which,

Fig. 1 is a bottom plan view of the invention.

35 Fig. 2 is a sectional view taken on substantially line 2—2 of Fig. 1, showing the arch in flexed condition,

Fig. 3 is a sectional view taken on substantially line 2—2 of Fig. 1, showing the arch 40 in flat position.

Fig. 4 is a sectional view taken on substantially line 4—4 of Fig. 1, with a part removed.

Fig. 5 is a bottom plan view of a modified form of the invention.

45 Fig. 6 is an enlarged fragmentary sectional view taken on substantially line 4—4 of Fig. 1.

Fig. 7 is a fragmentary bottom plan view with parts removed.

50 Fig. 8 is a perspective view of the operating lever used in a modified form.

In the preferred form, the arch support is illustrated as comprising a flexible foot engaging plate 7, which is preferably made 55 from leather. Mounted upon the under surface of the plate 7 is a metallic reinforcing

plate 8, which is preferably made from some resilient metal. Suitable rivets, or screws, serve to retain the plate 8 upon the plate 7, the rear of the plate 8 being secured at its 60 margin to the plate 7, as at 63, to avoid having any supporting attachment under the heel of the user. An adjusting plate 9 is mounted upon the plates 8 and 7 by the rivets 10 and 11, the plate 9, at the end through which the rivets 10 and 11 project, being fixed relatively to the reinforcing plate 8 and the flexible plate 7. Projected through the plate 7 and the reinforcing plate 8, at the rear end thereof, is a rivet or bolt 12. The plate 9 is 70 provided with a bead 13, at its rear end on the outer surface thereof. Adjacent the rear end there is formed in the plate 9 an opening 14 which is eccentric. As shown in Fig. 7, this opening 14 is formed eccentric and struck 75 throughout the major portion on a true circle, the opening being of such formation as would be obtained, were it struck on a true circle and then slightly bulged at one side. The bulge would be as shown in Fig. 7, at the laterally extending side 14'. Rotatably positioned on a rivet or bolt 12 is a disc 15, which has teeth 16 formed on its periphery, adapted for engagement with the pawl 17, which is mounted on the plate 9. The disc 15 is concentrically mounted on the bolt or rivet 12 and is provided on its undersurface with a circular boss 18, which is eccentric relatively to the rivet or bolt 12 and adapted for engaging in the opening formed in the plate 9. The 80 opening 14 is, on account of the bulge at 14', slightly larger than the diameter of the boss 18.

Secured to the plate 9 by screws 19 and 20 is a metallic plate 21, these screws projecting 95 through enlarged openings 20' formed in the plates 9 and 21. This plate 21 is provided, as shown in Fig. 1, with a plurality of tongues 22 along its marginal edges, these tongues being adapted for engaging the instep of the 100 foot when in use. In the form shown in Fig. 1, the tongues 22 are formed of a piece of metal which is secured between the plates 9 and 8 by the rivets or screws 19 and 20. Secured to the plate 9, by a screw 23 also projected through an enlarged opening in the plates 21 and 9 is a strip of reinforcing metal 24, which is adapted to engage at one end, with the upturned portion 25, the plate 21, this engagement being slightly within the 105 basis of the tongues 22. When these tongues 22 are formed from a separate piece of metal,

the engagement is with the upturned portion 25 against the separate piece of metal slightly within the base of the tongues 22. The other end of the strip 24 is upturned as at 25' and 5 in engagement with the plate 8.

The structure is such that, upon the turning of the disc 15, in the direction indicated by the arrows in Fig. 7, and in Fig. 1, the plate 9 will be shifted longitudinally in the 10 direction indicated by the arrow 9'', so as to be moved directly rearwardly of the plate 8 and the plate 8 buckling sufficiently to permit its movement. After the rearward movement of the plate 9, a transverse movement 15 in the direction of the arrow 9' is had, so that the plate 9 is moved into the position shown in dotted lines in Figs. 1 and 7. This movement of the plate 9 relatively to the plate 8 effects the flexing of the plate 8 and the plate 20 20 to give the various degrees of flexing to the arch. In this longitudinal and lateral shifting of the plate 9, the plate 9 exerts a pulling force on the plate 8 at the screw 11, tending to draw the end of the plate 8 toward 25 its rear end. The plate 9, at the same time, exerts a pushing effect on the plate 8 at the screw 10, tending to push the forward end of the plate 8 away from the rearward end. This movement results in a flexing longitudinally and transversely of the plates, so 30 that, as the plates are buckled to produce the curved effect at the center thereof, which is shown in Fig. 2, the plates are also curved slightly transversely to conform more accurately 35 to the shape of the foot. This movement is effected because of the formation of the opening 14 and the formation and mounting of the boss 18. With this movement, an adjustable arch support is provided, which is 40 adapted for conforming accurately to the contour of the foot in its varying degrees of adjustment, the angularity varying as the flexing upwardly of the arch is had.

In the modified form, I have shown the 45 plate 8' provided with a pair of connecting strips 29 and 30 mounted on the under surface of the plate 8'. The strip 30 is connected pivotally by the rivet 31 and the strip 29 is connected fixedly by the rivets 32 and 50 32'. The ends of the strips 29 and 30 are pivoted together by an eccentric having a lever 33 projecting therefrom. Upon a swinging of this lever, the loose ends of the strips 29 and 30 are brought into closer relation to each 55 other to effect a flexing of the plate 8'. A movement of the lever in the opposite direction serves to restore the plate to its flattened position. Holes 34 are provided in the plate 8', in which a stud projecting from the lever 60 33 may engage, to retain the members in their adjusted positions. The adjusting holes 34, co-operating with the stud, serve the same function as the pawl 17 cooperating with the teeth 16 on the disc 15. In this arrangement, 65 there is present the same pushing and pull-

ing effect, as shown in the preferred form. In the modified form each of the plates 29 and 30 is provided with an opening 29' and 30' respectively in which engages the eccentric shaped boss 35 which is mounted on the 70 lever 33.

As shown in the forms, in Figs. 1, 2 and 3, screws 19, 20 and 23 are used. These screws may be used for adjusting purposes as well as the eccentric boss 18. A threading of the 75 screws into the plate 8 will effect a further flexing of the plate 8 inasmuch as the plate 9 is drawn into closer proximity and the arch increased in this plate 9.

If desired, the screws mentioned may be 80 dispensed with and the auxiliary adjustment, just described, also dispensed with by adjusting the arch to the desired degree of flexing in the manufacture. In such a case the screws may be replaced by rivets. 85

The screws may also be used in the form shown in Fig. 5, the screws 65 and 66 serving to effect the additional adjustment. These screws may also be eliminated and replaced by rivets, if desired. In either case where 90 rivets are used, the holes 20', through which the rivets are projected through the plate 9 are formed sufficiently large to permit of a slight play so that the necessary relative movement between the plates 8 and 9 may be 95 had.

In the form shown in Fig. 5, it will be noted that the end of the plate 30 is terminated on substantially a straight line as at 64, as is also the end of the plate 8', as at 64'. It will 100 be noted that the plate 9 is also terminated at a slight angle to its longitudinal axis, this formation of these plates being desirable to accommodate the arch to the contour of the 105 foot.

While I have illustrated and described the preferred form of structure, I do not wish to limit myself to the precise form of structure shown but desire to avail myself of such 110 variations and modifications as come within the scope of the appended claims.

Having thus described my invention, what I claim as new and desire to secure by Letters Patent is:

1. An arch support of the class described, comprising: a flexible foot engaging plate; a reinforcing plate on said foot engaging plate; an adjusting plate mounted on said reinforcing plate, said adjusting plate being 120 fixed relatively to said reinforcing plate, at one of its ends, the opposite end of said adjusting plate having an opening provided therein; a bolt projected eccentrically through said opening; a disc mounted concentrically on said bolt; a circular boss on the inner surface of said disc, eccentrically of said bolt, adapted to engage in said opening, said adjusting plate being adapted to flex 125 said reinforcing plate and foot engaging 130

plate in two directions upon the rotation of said disc in one direction.

2. An arch support of the class described, comprising: a flexible foot engaging plate; a reinforcing plate mounted on said foot engaging plate; an adjusting plate on said reinforcing plate, said adjusting plate being fixed relatively to said reinforcing plate, at one of its ends, the opposite end of said adjusting plate having an opening provided therein; a bolt projected eccentrically through said opening; a disc mounted concentrically on said bolt; a circular boss on

the inner surface of said disc, eccentrically of said bolt, adapted for engaging in said opening, said adjusting plate being adapted to flex said reinforcing plate and foot engaging plate in two directions, upon the rotation of said disc in one direction; and an auxiliary plate, positioned between said reinforcing plate and said adjusting plate, and projecting outwardly from one side thereof. 15 20

In testimony whereof, I have signed the foregoing specification.

MATHIAS F. ROSER.
